UNITED STATES PATENT OFFICE.

JOHN M. THOMPSON, OF BUFFALO, NEW YORK.

STREET-FLUSHING APPARATUS.

1,184,274.

Specification of Letters Patent. Patented May 23, 1916.

Application filed November 15, 1913. Serial No. 801,313.

To all whom it may concern:

Be it known that I, JOHN M. THOMPSON, a citizen of the United States, residing at Buffalo, in the county of Erie and State of New York, have invented a new and useful Improvement in Street-Flushing Apparatus, of which the following is a specification.

This invention relates to apparatus for flushing and cleaning streets by means of a stream of water discharged from a nozzle. The cleaning of streets in this manner has heretofore been accomplished by means of a large flexible hose which is attached to a street hydrant. This requires a considerable force of men to drag the heavy hose from place to place on the pavement and to hold and manipulate the nozzle, and the dragging of the hose on the pavement rapidly wears out the same. This system was improved by replacing a part of the hose by a pipe line consisting of a plurality of flexibly connected pipe sections mounted on wheels to facilitate the moving of the same about on the street and to which a short length of hose having a discharge nozzle was connected. This system did not eliminate the dragging of some of the hose on the pavement with the consequent wear thereof, and it required more than one man to hold and manipulate the nozzle. Various power-operated means, such as motor trucks, have also been employed to support the nozzle and move the same from place to place, but these means are too unwieldy and cannot be readily shifted to bring the nozzle into any desired position.

The objects of this invention are to produce a street flushing apparatus adapted to be attached directly to a hydrant, in which the dragging of a flexible hose on the pavement is eliminated, but which can be readily moved and manipulated to direct the stream as may be necessary to properly clean the street; also to so construct the apparatus as to greatly reduce the number of men required to handle the same and manipulate the nozzle; also to arrange the discharge nozzle of the apparatus near the pavement to avoid the washing out of sand or filler from the crevices between paving stones.

In the accompanying drawings, consisting of two sheets: Figure 1 is a plan view of a street flushing apparatus embodying the invention. Fig. 2 is a side elevation of

the discharge end thereof. Fig. 3 is a sectional elevation, on an enlarged scale, of the discharge end of the apparatus on line 3-3, Fig. 1. Fig. 4 is an elevation, on an enlarged scale, of the end of the movable pipe section which is adapted to be connected with the pipe line, and the supporting truck therefor.

Briefly stated, the apparatus consists of a portable pipe line consisting of a number of flexibly connected pipe sections mounted on supporting wheels or trucks and a movable pipe section having a discharge nozzle swiveled thereon. The movable section is adapted to be connected with the pipe line at any one of a number of connectors, arranged at intervals on the pipe line, and is adapted to swing about its connection with the pipe line. The outer end of the movable section is supported by a truck or caster so that the operator is relieved of the weight thereof and of the nozzle in using the apparatus, and a handle is provided by which a single man can readily swing the movable pipe section and turn the nozzle to any desired position.

A represents a portable pipe line which consists of a plurality of pipe sections a which are connected at their ends by suitable unions or couplings a' , those employed in the construction shown including short lengths of flexible hose a^2 which enable the pipe line to pass around corners and to be shifted in position more or less. Each pipe section is mounted on wheels or trucks a^3 which may be secured on the sections in any suitable manner. One end of the pipe line is connected, preferably by means of a short flexible hose a^4 to a hydrant B. All of these parts of the pipe line may be of any suitable or usual construction.

C represents the movable pipe section, which is supported at its discharge end on a truck or carriage D which also supports a discharge nozzle E. The other end of the movable pipe section, which is connected with the pipe line A, is also preferably supported on a truck or carriage F.

The discharge end of the movable pipe section is connected to the nozzle in such a manner that the nozzle is free to swing horizontally about the end of the movable section, and this end of the pipe section together with the nozzle are mounted upon the truck D. In the construction shown, the discharge end of the movable pipe sec-

tion is swiveled to a casing G to which the discharge nozzle is also connected, and the casing is pivotally mounted on the truck D. A handle H, secured to the 5 casing G, serves to direct the nozzle and also to swing the movable pipe section C to any desired position. By means of this construction one man can direct the stream of water from the nozzle and can also move the nozzle 10 from place to place as desired.

The swivel connection between the casing G and the pipe section may be of any suitable construction. As shown, an elbow g is secured on the end of the movable pipe section 15 which is connected with a nipple g'. The nipple is held and adapted to turn in a stuffing box g² formed in the casing G. By means of this construction the nipple g' and the casing G are free to turn relatively to 20 each other on the axis of the nipple so that the nozzle can be turned to whatever position may be necessary to direct the stream of water in any desired direction. The nozzle may be secured to the casing G in any 25 suitable manner. Other means for rotatably connecting the end of the movable pipe section and the nozzle may be employed if desired.

The truck D, which supports the discharge 30 end of the movable pipe section and the nozzle, may be of any suitable construction. The truck shown in the drawings consists of a platform i on which wheels or casters i' are pivotally mounted, preferably on ball bearings i².

The casing G is preferably pivotally mounted on the truck D to further facilitate the movement of the nozzle, although the casing may be rigidly mounted on the truck 40 if desired. In the construction shown, a stud K is secured to the casing G and extends downwardly through a hole in the platform i.

The end of the movable pipe section C 45 which is connected with the pipe line A, may be swiveled directly with the pipe line to permit the pipe section C to swing relatively to the pipe line. It is, however, preferred to also mount this end of the pipe section on a truck so that the pipe section can be readily wheeled about when detached from the pipe line. For this reason this end of the movable pipe section is mounted upon the carriage F, which consists of a tube L 50 provided with supporting wheels l. The movable pipe section is connected with the tube L of the carriage by a swivel joint l' which may be of any suitable construction. The tube L has connected to it a short piece 55 of flexible hose l² provided with an ordinary hose coupling l³ at its end adapted to be connected with any one of a plurality of connectors l⁴ which are arranged at intervals 60 on the pipe line. The connectors may be of any suitable kind and are closed by caps l⁵

when the coupling l³ is not in connection therewith.

The wheels l may be connected to the short tube L in any suitable manner. In order to enable the carriage to adapt itself to rough or uneven pavements the wheels are preferably arranged in two pairs M M, each pair being journaled at m m on a ring m' which loosely embraces the short tube L and is free to turn on the tube. Each ring is held in 75 place between two collars m² m³ which are secured on the tube at opposite sides of the ring m' by set screws m⁴. Other means could be employed for mounting the carriage F on wheels.

In the operation of the device, the pipe line is drawn from hydrant to hydrant and the movable pipe section is connected first to one and then to another of the different connectors of the pipe line. The movable pipe section can be swung about its swivel connection substantially in the arc of a circle, as indicated in dotted lines in Fig. 1, and the nozzle can be swung in the arc of a circle about the discharge end of the movable pipe 90 section so that by these two relatively movable parts, any portion of a street can be reached by the stream of water from the nozzle. The movable pipe section, mounted on trucks or wheels, replaces the hose heretofore used 95 and is much more durable and less liable to wear out than the hose. The mounting of the movable pipe section on trucks enables the same to be easily drawn about on the street when disconnected from the pipe line 100 and greatly reduces the labor required to operate the apparatus. With the construction described, one man can direct the nozzle by means of the handle H and can at the same time move the discharge end of the movable pipe section about. In using a flexible hose 105 a considerable force of men is required to handle the nozzle, owing to the tendency of the hose to straighten itself out when water under pressure flows through it. By making the movable part of the apparatus of rigid pipes or tubes, the number of men required to handle the nozzle is greatly reduced since this tendency is resisted by the 110 rigidity of the movable pipe. The arranging of the nozzle near the pavement as described prevents the washing of the sand from between the paving stones, which frequently occurs with flushing apparatus in 115 which the nozzle is held at a considerable 120 distance above the ground. The provision of the flexible hose l² and the hose coupling l³ enables the movable pipe section to be quickly and easily connected to the pipe line at any desired connector. When moving the 125 apparatus to and from the work the movable pipe section C can be disconnected from its two trucks, thus enabling these parts to be separately handled and reducing the labor of lifting and carrying the parts.

I claim as my invention:

1. In a street flushing apparatus, the combination of a pipe line adapted to be moved along a street and to be connected with a source of water supply, a rigid pipe section, a plurality of connectors arranged at intervals along said pipe line and to any one of which one end of said pipe section is adapted to be connected, said pipe section being movable to different angular relations to said pipe line when connected thereto, means for supporting the other end of said pipe section independently of the pipe line, and a discharge nozzle at said other end of the pipe section.
2. In a street flushing apparatus, the combination of a pipe line adapted to be moved along a street and to be connected with a source of water supply, a plurality of connectors arranged at intervals on said pipe line, a rigid pipe section adapted to be connected at one end with any one of said connectors and movable to different angular relations to the pipe line, a truck on which said pipe section is mounted independently of said pipe line, and a discharge nozzle on said pipe section.
3. In a street flushing apparatus, the combination with a pipe line movable along a street and provided with a plurality of coupling means between the ends thereof, of a rigid pipe section adapted to be connected at one end with any one of said coupling means and movable to different angular relations to the pipe line, means for supporting the other end of the pipe section, and a discharge nozzle at said other end of the pipe section.
4. In a street flushing apparatus, the combination with a pipe line movable along a street and provided with a plurality of coupling means between the ends thereof, of a rigid pipe section adapted to be connected at one end with any one of said coupling means and movable to different angular relations to the pipe line, means for supporting the other end of the pipe section, and a discharge nozzle pivoted to the other end of the pipe section and supported on said supporting means.
5. In a street flushing apparatus, the combination with a pipe line movable along a street and provided with a plurality of coupling means between the ends thereof, of a rigid pipe section adapted to be connected at one end with any one of said coupling means, a swivel connection at said end of the pipe section, a discharge nozzle swiveled to the other end of the pipe section, and means pivotally connected with and supporting said other end of the pipe section.
6. In a street flushing apparatus, the combination with a pipe line provided at intervals throughout its length with coupling means, of a rigid pipe section adapted to be

connected at its receiving end with any one of said coupling means and swiveled at said receiving end to permit the pipe section to swing to different angular relations to the pipe line, a discharge nozzle on said movable pipe section which is movable to different angular relations to said pipe section, means for supporting the receiving end of said pipe section, and a truck on which the nozzle and the discharge end of said pipe section are mounted.

7. In a flushing apparatus, the combination with a pipe line provided at intervals throughout its length with coupling means, of a rigid pipe section adapted to be connected at one end with any one of said coupling means and movable to different angular positions relatively to said pipe line, and a truck supporting the other end of the pipe section, said truck including a platform which is swiveled to said pipe section and caster wheels on which said platform is mounted and which are connected with said platform to swing about substantially upright axes.

8. In a flushing apparatus, the combination with a pipe line provided at intervals throughout its length with coupling means, of a rigid pipe section adapted to be connected at one end with any one of said coupling means and movable to different angular positions relatively to said pipe line, a discharge nozzle having a swivel connection with the other end of said pipe section, and a caster wheel which is adapted to swing on a substantially vertical axis and on which said discharge nozzle is pivotally mounted.

9. In a street flushing apparatus, the combination with a source of water supply, of a rigid pipe section movably connected at its receiving end with said source of supply, a discharge nozzle having a swivel connection with the other end of said pipe section, a caster supporting said other end of said pipe section, and a handle connected with said nozzle for turning said nozzle and for moving said pipe section.

10. In a street flushing apparatus, the combination with a source of water supply, of a rigid pipe section movably connected at its receiving end with said source of supply, a discharge nozzle having a swivel connection with the other end of said pipe section, a caster supporting said other end of said pipe section and mounted to swing about a substantially upright pivot, and a handle connected with said nozzle for turning said nozzle and for moving said pipe section.

11. In a flushing apparatus, the combination with a source of water supply, of a rigid pipe section movably connected at its receiving end with said source of water supply, a discharge nozzle, a supporting platform for the discharge nozzle and for the

discharge end of said pipe section, said platform, nozzle and pipe section being pivotally connected to swing freely relatively to each other, and casters on which said 5 platform is mounted.

12. In a flushing apparatus, the combination with a pipe line, of a truck having a chamber adapted to be connected with said pipe line at any one of a number of points 10 arranged at intervals along said pipe line, a rigid pipe section connected with said chamber and adapted to turn relatively to said truck, a truck supporting the outer end of said pipe section, and a discharge 15 nozzle swiveled to said pipe section.

13. In a street flushing apparatus, the combination of a pipe line, wheels on which the pipe line is mounted and which adapt the same to be moved along a street, a plurality of connectors arranged on said pipe 20 line at intervals throughout the length thereof, a movable rigid pipe section mounted on casters and adapted to be connected with any of said connectors, and a discharge 25 nozzle having a swiveled connection with said pipe section.

14. In a flushing apparatus, the combination of a rigid pipe section, supporting means for the receiving end of said pipe section and relatively to which said pipe section is movable, a discharge nozzle swiveled to the other end of said pipe section, a caster wheel having a swiveled connection with said discharge nozzle, and means connected 30 to said discharge nozzle for directing said 35 to said discharge nozzle for directing said

nozzle and for moving said other end of the pipe section.

15. In a flushing apparatus, the combination of a rigid pipe section, supporting means for the receiving end of said pipe section and relatively to which said pipe section is movable, a discharge nozzle swiveled to the other end of said pipe section, a platform swiveled to said discharge nozzle, 40 caster wheels supporting said platform, and means connected to said discharge nozzle for directing said nozzle and for moving the discharge end of said pipe section.

16. In a flushing apparatus, the combination with a source of water supply, of a pipe 50 line adapted to be moved along the street and to be connected with said source of water supply, a truck, a conduit mounted on said truck and adapted to be connected with said pipe line, a rigid pipe section 55 swiveled at one end to said conduit and adapted to receive water therefrom, a discharge nozzle swiveled to the other end of said pipe section, a caster wheel having a swivel connection with said discharge nozzle, and means connected to said discharge 60 nozzle for directing said nozzle and for moving said other end of the pipe section.

Witness my hand, this 29th day of October, 1913.

JOHN M. THOMPSON.
